UNITED STATES PATENT OFFICE

2,069,761

HEATER

John T. Hyde, Oak Park, Ill.

Application February 28, 1935, Serial No. 8,610

7 Claims. (Cl. 122—356)

This invention relates to heat exchange devices, and particularly to a device of the character described, which is particularly well adapted for heating water or other fluids.

One object of the present invention is to provide a novel construction and arrangement whereby water may be quickly heated to a high degree.

Another object of the invention is to provide a construction and arrangement whereby heat which would otherwise be wasted is employed to enhance the efficient operation of the device.

Another object of the invention is to provide a construction and arrangement whereby the rapid heating of the water is greatly accelerated.

Another object of the invention is to provide a novel construction and arrangement whereby the use of insulating material for the device is obviated.

Another object of the invention is to provide a device of the character described wherein a pre-heater and a main heater are efficiently related and compactly built into a novel unitary structure.

A further object of the invention is to provide novel ventilating means to prevent damage to the device by reason of the expansion and contraction thereof, and wherein novel means are provided for supporting the fluid conducting elements and for efficiently directing the heat thereto.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is a sectional elevational view of a water heating device embodying features of the present invention;

Fig. 2 is a transverse sectional plan view on a reduced scale, and taken substantially as indicated by the line 2—2 of Fig. 1; and

Fig. 3 is a fragmentary sectional perspective view through a portion of one of the fluid conduits, and taken substantially as indicated by the line 3—3 of Fig. 1.

The illustrative embodiment of the present invention comprises a housing indicated, as a whole, by the numeral 5 having vertically disposed side walls 6 and 7 and a top member 8 shown, in the present instance, as provided with an outlet 9 by which the products of combustion may be removed from the interior of the housing, a burner

11 being positioned in the lower portion thereof and connected by means of a pipe 12 to a suitable source of fuel supply.

Positioned in the upper portion of the housing 5 are a series or plurality of flattened fluid conduits comprising a pre-heater A, the respective conduits being indicated, as a whole, by the numeral 13, and shown, in the present instance, as comprising a portion or element 14 of substantially straight cross section and a portion or element 15 depressed intermediate its longitudinal edge portions, and adapted to be secured by welding or other suitable means adjacent its edge portions to the edge portions of the member 14 as clearly illustrated in Figs. 2 and 3.

The conduits 13 are shown as of corrugated or zigzag form, thereby providing fluid passages of considerable length in a limited space, and held in spaced relation with respect to each other by means of a spacer 16 in a manner to form a plurality of zigzag passages of considerable length between the respective conduits, the lower end portions of the conduits 13 being connected to and adapted to communicate with a fluid intake pipe 17 extending into the housing 5 intermediate its end portions, while the upper end portion of the conduits 13 are adapted to communicate with a fluid conductor 18 shown, in the present instance, as extending outside the housing 5 from the upper to the lower portion 30 thereof.

Positioned also in the housing 5 adjacent the lower portion thereof and between the burner 11 and the fluid inlet pipe 17, are a series or plurality of zigzag fluid conduits 19 comprising a main heater B, the respective conduits 19 being held in spaced relation with respect to each other by a spacer 21 in a manner to provide a plurality of zigzag passages above the burner 11 adapted to communicate adjacent their upper end portions with the passages formed between the fluid conduits 13 in the upper portion of the housing in a manner to conduct the products of combustion from the burner 11 through circuitous routes to the outlet 9, the lower end portions of the conduits 19 being adapted to communicate with the fluid conductor 18, and at their upper end portions with a fluid discharge pipe 22 positioned preferably adjacent the fluid inlet pipe 17.

It will be noted that the corrugated portions of the respective conduits 13 and 19 are positioned in overlapping relationship, and that by reason of this fact, all the products of combustion, in their upward travel, are directed along

the entire length of the straight portions of the corrugations.

It will be observed that by such an arrangement, a pre-heater for the fluid is provided by the conduits 13 in the upper portion of the housing, and a main heater provided by the fluid conduits 19 in the lower portion thereof, the two being connected by means of the conduits 18.

By such an arrangement, it will be observed also that the water entering through the inlet pipe 17 will be pre-heated to a certain degree in its passage upwardly through the conduits 13, after which it passes through the conductor 18 to the lower end portions of the main heater provided by the conduits 19 in the lower portion of the housing, where it is subjected to a high degree of heat from the burner 11 just prior to its discharge from the device through the fluid outlet pipe 22, the pre-heating of the fluid in the conduits 13 serving to materially accelerate the final heating of the fluid in its passage through the conduits 19, thereby providing a structure which is economical in the amount of fuel consumed and efficient in its operation by reason of its ability to quickly supply water or other fluid having a desirable high degree of heat.

It will be observed further, particularly by reference to Fig. 1 of the drawing, that by reason of the relationship of the outer conduits 13 and 19, of the units A—B, with respect to the side walls 6, a plurality of air spaces S are provided adjacent the walls to serve as a heat insulation for the device.

35. For ventilating air spaces S within the housing 5 formed by the outer conduits 13 and 19, the wall portions 6 of the housing 5 are provided with openings 23 and 24, the openings 23 being formed, preferably, by removing therefrom the struck-up portions 25 formed integrally with the side walls 6 of the housing 5 and bent inwardly in a manner to provide supports for the series of conduits of the pre-heater A and main heater B formed by the conduits 13 and 19, respectively.

Positioned within the housing adjacent the burner 11 are a plurality of guide members 26 for directing the products of combustion from the burner into the passages formed between the respective conduits 19 of the main heater.

It will be observed from the foregoing description that the present invention provides a novel construction and arrangement in water heaters, for example, whereby water may be quickly heated and the heating process greatly accelerated, also that a pre-heater and main heater are efficiently related in a compact unitary structure, and that suitable ventilating means are provided to prevent undue expansion and contraction of the device due to changes in temperature.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to secure by Letters Patent is:

1. In a water heater, the combination of a housing having an outlet, a burner in said housing, a plurality of series of vertically disposed zigzag fluid conduits positioned in superposed relation in said housing, said conduits of the re-

spective series being spaced with respect to each other to provide a plurality of continuous circuitous passages throughout the vertical length of the housing for passing the products of combustion from said burner to said outlet, fluid conducting means connecting the upper end of the upper of said series of conduits with the lower end of the lower of said series, and fluid inlet and discharge pipes at the adjacent ends of said plurality of series and connected, respectively, to the lower end of said upper series and the upper end of said lower series.

2. In a water heater, the combination of a housing having an outlet adjacent its upper end and ventilating openings in the side walls of the housing intermediate its ends, a burner in said housing adjacent the lower end thereof, a plurality of series of vertically disposed flattened zigzag conduits having overlapping corrugated portions and positioned in superposed relation in said housing between said burner and outlet, said conduits being spaced in substantially parallel relation with respect to each other to provide a plurality of circuitous passages for the products of combustion passing from said burner to said outlet, fluid conducting means connecting the upper end of the upper of said series of conduits with the lower end of the lower of said series, and fluid inlet and discharge pipes at the adjacent ends of said plurality of series and connected, respectively, to the lower end of said upper series and to the upper end of said lower series.

3. In a water heater, the combination of a housing having an outlet adjacent its upper end and a plurality of ventilating openings in the side walls of said housing intermediate its ends, a burner in said housing adjacent its lower end portion, a fluid inlet pipe positioned in said housing intermediate the ends thereof, a plurality of vertically disposed zigzag fluid conduits positioned in the upper portion of said housing and communicating adjacent their lower ends with said inlet pipe, said conduits being spaced with respect to each other to provide a plurality of circuitous passages therebetween, a plurality of vertically disposed zigzag fluid conduits in the lower portion of said housing, said lower conduits being spaced with respect to each other to provide a plurality of circuitous passages above said burner communicating at their upper ends with the passages between said upper conduits, fluid conducting means connecting the upper end portions of the upper conduits with the lower end portions of the lower conduits, and a fluid discharge pipe communicating with the upper end portions of said lower conduits.

4. In a water heater, the combination of a housing having an outlet adjacent its upper end portion, a burner in said housing adjacent its lower end portion, a fluid inlet pipe positioned in said housing intermediate the ends thereof, a plurality of vertically disposed zigzag fluid conduits providing a pre-heater in the upper portion of said housing communicating at its lower end portion with said inlet pipe, said conduits being spaced with respect to each other to provide a plurality of circuitous passages therebetween, a plurality of vertically disposed zigzag fluid conduits providing a main heater in the lower portion of said housing, said lower conduits being spaced with respect to each other to provide a plurality of circuitous passages above said burner communicating at their upper ends with the passages between said upper conduits, fluid con-

ducting means connecting the upper end portion of said pre-heater with the lower end portion of said main heater, and a fluid discharge pipe communicating with the upper end portion of 5 said main heater.

5. In a water heater, the combination of a housing having an outlet adjacent its upper end and a plurality of ventilating openings in the walls of the housing intermediate its ends, a 10 burner in said housing adjacent its lower end portion, a fluid inlet pipe positioned in said housing intermediate the ends thereof, a plurality of vertically disposed zigzag fluid conduits positioned in the upper portion of said housing and communicating adjacent their lower ends with said 15 inlet pipe, said conduits being horizontally spaced with respect to each other to provide a plurality of circuitous passages therebetween, a plurality of vertically disposed zigzag fluid conduits in the 20 lower portion of said housing, said lower conduits being horizontally spaced with respect to each other to provide a plurality of circuitous passages above said burner communicating at their upper ends with the passages between said 25 upper conduits, fluid conducting means connecting the upper end portions of the upper conduits with the lower end portions of the lower conduits, an outlet pipe communicating with the upper 30 end portions of said lower conduits, and inclined guide members adjacent said burner for directing the products of combustion therefrom into said 35 passages.

6. In a water heater, the combination of a housing having an outlet adjacent its upper end and a plurality of ventilating openings in certain 35 side walls of the housing intermediate its ends, a burner in said housing adjacent its lower end portion, a fluid inlet pipe positioned in said housing intermediate the ends thereof, a series of vertically disposed zigzag fluid conduits positioned in the upper portion of said housing and communicating adjacent their lower ends with 40 said inlet pipe, said conduits being spaced with respect to each other to provide a plurality of

circuitous passages therebetween, a series of vertically disposed zigzag fluid conduits in the lower portion of said housing, said lower conduits being spaced with respect to each other to provide a plurality of circuitous passages above said burner 5 communicating at their upper ends with the passages between said upper conduits, means for connecting and spacing the conduits of the respective series, fluid conducting means connecting the upper end portions of the upper conduits 10 with the lower end portions of the lower conduits, an outlet pipe communicating with the upper end portions of said lower conduits, and means formed integrally with said housing adjacent 15 said ventilating openings for supporting the respective series of conduits in the housing.

7. In a water heater, the combination of a housing having an outlet adjacent its upper end and a plurality of ventilating openings in the side walls of the housing intermediate its ends, 20 a burner in said housing adjacent its lower end portion, a fluid inlet pipe positioned in said housing intermediate the ends thereof, a plurality of vertically disposed flattened zigzag fluid conduits positioned in said housing above said inlet 25 pipe and communicating therewith adjacent their lower ends, said conduits being spaced with respect to each other to provide a plurality of circuitous passages therebetween, a plurality of zigzag fluid conduits in said housing below said inlet pipe, said last mentioned conduits being vertically disposed and spaced with respect to each other to provide a plurality of circuitous 30 passages above said burner and communicating at their upper ends with the passages between the conduits above said inlet pipe, fluid conducting means connecting the upper end portions of the conduits above the inlet pipe with the lower end portions of the conduits below said inlet pipe, and a fluid discharge pipe communicating 35 with the upper end portions of said last mentioned conduits.

JOHN T. HYDE.
